THREAD CASES FOR SEWING MACHINE
LOOP-TAKERSGeorge A. Fleckenstein, Stratford, Conn., assignor
to The Singer Manufacturing Company, Eliza-
beth, N. J., a corporation of New Jersey

Application December 29, 1932, Serial No. 649,317

21 Claims. (Cl. 112—231)

This invention relates to improvements in thread-cases for sewing machine loop-takers and has for an object to provide readily releasable means for securely locking together the component sections of a thread-case. A further object of the invention is to provide convenient threading means for a thread-case designed to deliver thread at a uniform tension. Other and more specific objects of the invention will be apparent from the following description and claims.

10 The invention consists in the devices, combinations and arrangements of parts hereinafter described in connection with the accompanying drawing which illustrates a preferred embodiment of the invention and in which:

15 Fig. 1 represents a vertical section of a sewing machine loop-taker, with the thread-case therein in side elevation. Fig. 2 represents a top-plan view of the thread-case. Fig. 3 is a cross-section 20 of the thread-case, substantially on the broken line 3—3 of Fig. 2. Fig. 4 represents a bottom plan view of the cap-section of the thread-case. Fig. 5 represents a top perspective view of the 25 cap-section with the latch device in released position. Fig. 6 represents a top perspective view 30 of the base-section of the thread-case. Fig. 7 represents perspective views of the cap-section and a cap shown detached from the cap-section, and illustrating the lead of the thread from the center of the cap to the thread-guide within said cap-section.

35 Referring to the drawing, the sewing machine loop-taker employed for cooperation with a vertically reciprocatory needle 1 may be of any usual or suitable construction, Fig. 1 illustrating a loop-taker of the vertical-axis rotary hook type and disclosed more fully, for example, in the U. S. patent to W. N. Parkes, No. 1,763,670, June 17, 1930. In general, the loop-taker shown in the 40 accompanying drawing has an outer cylindrical body 2 formed at its upper end with an inwardly directed flange 3 spaced from a similar flange 4 constituting the upper rim of an inner loop-taker body 5 to which the outer body 2 is secured by screws 6. The flanges 3 and 4 of the loop-taker define therebetween a raceway in which is journaled a bearing-rib 7 upon the periphery of a base-section 8 of a two-part thread-case comprising said base-section and a cap-section 9.

45 The base-section 8 of the thread-case is cup-shaped, having a cylindrical side wall 10 open at its top, and in the present instance provided with a bottom closing or end wall 11 free of internal projections. The bearing-rib 7 of the base-section 50 55 8 is interrupted to provide a thread-loop ar-

resting shoulder 12 and an opposed shoulder 13 defining therebetween a thread-loop clearance gap. Below the bearing rib 7 and slightly rearwardly of the shoulder 12 in the direction of rotation of the loop-taker, the side wall 10 of the base-section is provided with an auxiliary hook 14 which functions to detain one limb of the needle-thread loop and thereby assist in casting said loop about the bottom of the thread-case.

55 Above the bearing rib 7, the base-section side wall is provided with a notch 15 for the reception of a stationary stop-member (not shown) serving to restrain the thread-case against rotation with the loop-taker. At one side of the 60 notch 15, the base-section 8 has an upwardly inclined flange 16 terminating in the upper rim of the side wall 10, said flange assisting in the casting of a limb of the needle-thread loop about the upper face of the thread-case. The flange 16 65 is preferably provided with a plurality of oil-wells 17 of the character disclosed more fully in the U. S. patent to W. N. Parkes, No. 1,698,965, Jan. 15, 1929.

70 At the other side of the notch 15, the side wall 10 of the base-section above the bearing rib 7 is cut away to provide a cap-locating notch defined by the downwardly inclined shoulder 18 and the opposed shoulder 19 of said side wall 10. Directly adjacent to said shoulder 19 and also at 75 a point diametrically opposite, the side wall 10 is provided above the bearing-rib 7 with apertures 20 and 21 of which the walls serve as latch-keepers. The flange 16 terminates at one end in a shoulder 22 engageable by an opener-finger (not shown) to open a thread-loop passage past the thread-case rotation restraining means before mentioned.

80 While it will be observed from the foregoing description that the base-section of the thread-case contains many of the constructive features of the bobbin-carrier of the Parkes Patents Nos. 1,698,965 and 1,763,670, the present thread-case 85 additionally includes the cup-shaped cap-section 9. This cap-section 9 has a cylindrical side-wall 23 open at its bottom and fitting into the base-section 8. The cap-section 9 has a top-closing end wall 24 which in the present instance is integral with the side wall 23. To the inner face of the end wall 24 is brazed or otherwise flatwise secured a disk 25 of which a substantially semi-circular segment is reduced in thickness to provide a tongue 26 spaced from the inner face of the top wall 24. The segmental tongue 26 is 90 also cut away peripherally so that its free edge 100 105 110

27 is spaced slightly from the cap-section side wall 23. In addition, the tongue 26 is provided with an arcuate threading slit 28 beginning in the edge of the tongue at the point of its juncture 5 with the thicker portion of the disk 25 and terminating at substantially the center of said disk, i. e., centrally within the cap-section body in a thread-guiding pocket 28'. As illustrated more particularly in Figs. 4 and 7 of the drawing, the 10 peripheral edge 27 and one of the side edges of the slit 28 of the tongue 26 meet in a pointed nose 29 extending into but spaced from the edges of a vertically inclined threading slot 30 formed in the side wall 23 of the cap-section and extending 15 from the lower rim thereof. The thread-guide 28' connects the thread-cavity of the cap-section with the thread-channel formed by spacing the tongue 26 from the end wall 24.

Substantially diametrically opposite to its slot 20 30, the cap-section side wall 23 is provided with a vertically inclined threading slit 31 beginning in the lower edge of said side wall and running past the edge 27 of the segmental tongue 26, at a point directly adjacent to the thicker portion 25 of the disk 25. The slit 31 extends into a segmental flange 32 projecting radially outwardly beyond the side wall 23 of the cap-section from the top wall thereof. The flange 32 is adapted to fit into the base-section rim notch between 30 the shoulders 18 and 19 to thereby definitely locate the cap-section in the base-section. Secured by screws 33 upon the flange 32 is a tension-spring 34 which extends across the threading slit 31 and has at one end a thread-delivery notch 35. The threading slit 31 is preferably inclined upwardly toward the tension-spring notch to facilitate threading of the cap-section.

Slidably disposed in undercut alined guideways 36 and 37 provided in the upper face of the cap-section end wall 24 are oppositely directed 40 latch-members 38 and 39 shouldered at their outer ends to provide latch-lugs 40 and 41 adapted to enter the keeper-apertures 20 and 21 of the base-section. The latch-members 38 and 39 are retained in their guideways by having side flanges slidably disposed in the undercut portions of the guideways, said latch-members being also provided at one of their side edges and at adjacent ends thereof with abutment shoulders 42 and 43 45 acted upon by opposed springs 44 and 45. The springs 44 and 45 are housed within said end wall 24, being disposed in a bore 46 extending across the wall 24 adjacent to the guideways 36 and 37. The springs 44 and 45 are confined within the 50 bore 46 by screws 47 threaded into the opposite ends of the bore, said screws 47 also providing for adjustment of the pressures of said springs.

Interposed between the adjacent ends of the latch-members 38 and 39 is a cam-arm 48 of an 60 angular latch-lever 48, 49, said cam-arm 48 being pivotally supported by a pivot-pin 50 extending transversely of the guideways 36 and 37. The pivot-pin 50 is disposed in the cap-section end wall 24 so that the latch-lever cam-arm 48 is 65 substantially flush with the upper face of the end wall 24 in the keeper-engaging positions of the latch-members 38 and 39, said latch-lever 48, 49 being disposed in an angular clearance recess 52 provided in the outer face of the end wall 24. The operating arm 49 of the latch-lever is adapted to enter a portion of the recess 52 directly adjacent and parallel to the guideway 36 of the latch-member 38, a stop-pin 54 in the bottom of said recess 52 positioning the operating arm 49 substantially flush with the end wall 24

in the closed position of the latch. The free end of the latch-arm 49 is preferably made segmental to conform with the circular side wall 23 of the cap-section, and is also preferably beveled on its under side so that it may be more conveniently picked up. The upper rim of the base-section side-wall is also preferably beveled adjacent to the free end of the latch-arm to facilitate access to said latch-arm.

The present thread-case is particularly adapted 80 for use with a thread-cop 55 adapted to snugly fit the side walls of the cap-section 9 and having its thread so wound that it may be freely drawn from the center of the cop. Before placing the cop 55 in the cap-section, a suitable length of thread is drawn from the center of the cop, passed into the threading slot 30 and under the nose 29 of the tongue 26, about the edge 27 of the latter into the channel between the end wall 24 and the tongue 26, through the threading slit 31 and under the tension-spring 34 to the delivery notch 35 thereof. In the retracted position of the latch-members 38 and 39, the latch-lever 48, 49 is edgewise substantially vertical, the arm 49 thereof affording convenient means for grasping 90 the cap-section to insert it in the base-section and to remove it therefrom. After the cap-section has been threaded as described and the cop 55 has been placed therein, the cap-section is inserted into the base-section with the lower edge 100 of the cap-section side wall 23 preferably engaging the bottom wall 11 of the base-section. Of course, the insertion of the cap-section into the base-section can only be completed when the segmental flange 32 is positioned to enter the 110 notch between the shoulders 18 and 19 of the base-section, and when thus positioned, the latch-member lugs 40 and 41 are in alinement with the keeper-apertures 20 and 21 of the base-section. By now turning the latch-lever down, the arm 115 48 of said latch-lever cams the latch-members outwardly to lock together the component sections of the thread-case. The latch-members and the latch-lever are substantially flush with the outer face of the cap-section end wall when 120 the cap-section is latched to the base-section, and accordingly the latch-members do not impede the passing of the needle-thread loop about the thread-case by the loop-taker. By the described threading arrangement, the thread supplied by the cop 55 is drawn constantly against the end of the slot 28 centrally of the thread-case. Consequently the thread is always drawn from the exact center of the cop with a kink straightening action and a minimum tendency to 125 snarl, regardless of the increasing size of the cop aperture as the thread is drawn therefrom.

Having thus set forth the nature of the invention, what I claim herein is:—

1. A thread-case for sewing machine loop-takers, comprising a base-section having a cylindrical side wall provided with a keeper, a cap-section adapted to be associated with said base-section in thread-mass confining relationship and having an end wall, a latch-member slidably disposed upon said cap-section end wall for engagement with said keeper, a latch-member operating lever pivotally mounted upon said cap-section end wall and disposed in substantially the plane of said latch-member in the keeper-engaging position of the latch-member, and a spring acting in opposition to said lever to yieldingly retract said latch-member from keeper-engaging position.

2. A thread-case for sewing machine loop-

- takers, comprising a base-section having a cylindrical side wall provided with a keeper, a cap-section having a cylindrical side wall interfitting with said base-section side wall and having an end wall provided in one face thereof with a guideway and an angular clearance recess intersecting said guideway, a latch-member slidably disposed in said guideway substantially flush with said face of the cap-section end wall for engagement with said keeper, and an angular latch-member operating lever pivotally mounted upon said cap-section end wall and disposed in said clearance recess substantially flush with said face of the cap-section end wall in the keeper engaging position of said latch-member. 5
3. A thread-case for sewing machine loop-takers, comprising a base-section having a cylindrical side wall provided with a keeper, a cap-section having a cylindrical side wall interfitting with said base-section side wall and having an end wall, a latch-member slidably disposed upon said cap-section end wall for engagement with said keeper, a latch-member operating lever pivotally mounted upon said cap-section end wall, said lever having a cam-arm in engagement with said latch-member and having an operating arm disposed at one side and substantially in the plane of said latch-member in the keeper-engaging position of the latch-member, and a spring 20 housed within said cap-section end wall acting to yieldingly retract said latch-member from keeper-engaging position. 25
4. A thread-case for sewing machine loop-takers, comprising separable base and cap thread-case sections, and means for securing one of said thread-case sections to the other in thread-mass confining relationship comprising a plurality of latch-members, keepers for said latch-members, and a manually operable actuating lever disposed to operatively engage said latch-members. 30
5. A thread-case for sewing machine loop-takers, comprising separable base and cap thread-case sections, means for securing one of said thread-case sections to the other in thread-mass confining relationship comprising a plurality of latch-members, keepers for said latch-members, a manually operable actuating lever disposed to simultaneously engage said latch-members, and guiding means for insuring a predetermined associated relationship of said thread-case sections. 45
6. A thread-case for sewing machine loop-takers, comprising separable base and cap thread-case sections, a plurality of latch-members carried by said cap-section, a plurality of keepers upon said base-section for engagement by said latch-members, and single manually operable means for effecting engagement of said latch-members with said keepers. 50
7. A thread-case for sewing machine loop-takers, comprising separable base and cap thread-case sections, a plurality of oppositely directed latch-members slidably disposed upon one of said sections, keepers upon the other section for engagement by said latch-members, and manually operable means disposed between said latch-members for effecting engagement of the latch-members with said keepers. 55
8. A thread-case for sewing machine loop-takers, comprising separable base and cap thread-case sections, a plurality of latch-members upon one of said sections, keepers upon the other section for engagement by said latch-members, manually operable means for effect- 60
- ing engagement of said latch-members with said keepers, and means acting to yieldingly oppose keeper-engaging movements of said latch-members. 65
9. A thread-case for sewing machine loop-takers, comprising separable base and cap thread-case sections, a plurality of oppositely directed latch-members upon one of said sections, keepers upon the other section for engagement by said latch-members, and a latch-lever disposed between said latch-members and operable to simultaneously move said latch-members into engagement with said keepers. 70
10. A thread-case for sewing machine loop-takers, comprising separable base and cap thread-case sections, a plurality of oppositely directed latch-members upon one of said sections, keepers upon the other section for engagement by said latch-members, a latch-lever disposed between said latch-members and operable to simultaneously move said latch-members in opposite directions into keeper-engaging position, and means acting to yieldingly oppose the keeper engaging movements of said latch-members. 75
11. A thread-case for sewing machine loop-takers, comprising separable base and cap thread-case sections having cylindrical interfitting side walls and opposed end walls defining a thread mass cavity, a plurality of oppositely directed latch-members slidably disposed in substantial alinement diametrically upon the cap-section end wall, a plurality of keepers for said latch-members upon said base-section, and a latch-lever operable to move said latch-members in opposite directions into engagement with said keepers. 80
12. A thread-case for sewing machine loop-takers, comprising a base-section provided with a plurality of keepers, a cap-section adapted to be associated with said base-section in thread-mass confining relationship and having an end wall, a plurality of latch-members arranged substantially flush with a face of said cap-section end wall, and single manually operable means for effecting engagement of said latch-members with said keepers. 85
13. A thread-case for sewing machine loop-takers, comprising a base-section provided with a plurality of keepers, a cap-section adapted to be associated with said base-section in thread-mass confining relationship, a plurality of latch-members slidably disposed upon said cap-section end wall substantially flush with the outer face of said wall for engagement with said keepers, and an operating lever for said latch-members disposed substantially flush with said outer face of the cap-section end wall in the keeper engaging positions of said latch-members. 90
14. A thread-case for sewing machine loop-takers, comprising a base-section having a cylindrical side wall provided with diametrically opposed keepers, a cap-section having a cylindrical side wall interfitting with said base-section side wall and having an end wall diametrically provided with aligned guideways, oppositely directed latch-members slidably disposed in said guideways for engagement with said base-section keepers, a latch-member operating lever pivotally supported between adjacent ends of said latch-members, and springs arranged to yieldingly oppose the movements of said latch-members into keeper engaging positions thereof. 95
15. A thread-case for sewing machine loop-takers, comprising a base-section having a cylin- 100

16. A thread-case for sewing machine loop-takers, including a thread-cavity defining cup-shaped body having a cylindrical side wall and an end wall integral with said side wall, a thread-guide disposed centrally within said body adjacent to and spaced from said end wall at the thread-cavity side thereof, said side wall having a threading slit extending from the rim at the open end of said cup-shaped body toward said end wall, and thread-tensioning means carried by said body.
17. A thread-case for sewing machine loop-takers, including a thread-cavity defining cup-shaped body having a cylindrical side wall and an end wall integral with said side wall, a tongue disposed within said body adjacent to and spaced from said end wall, said tongue having a threading slit extending from one edge of the tongue and terminating in a thread-guide disposed centrally within said body, and said side wall having a threading slit extending from the rim at the open end of said cup-shaped body toward said end wall.
18. A thread-case for sewing machine loop-takers, including a thread-cavity defining cup-shaped body having a cylindrical side wall and an end wall, said end wall being recessed edge-wise to provide a segmental tongue substantially parallel with and spaced from a portion of said end wall to define a thread-channel, said tongue having a threading slit extending from one edge thereof and terminating in a thread-guide disposed centrally within said body, and said side wall having a threading slit extending from the rim at the open end of said cup-shaped body into the plane of said thread-channel.
19. A thread-case for sewing machine loop-takers, including a thread-cavity defining cup-shaped body having a cylindrical side wall and an end wall at the thread-cavity side thereof, said side wall having a threading slit extending from the rim at the open end of said cup-shaped body toward said end wall, and a tension-spring upon the outer face of said body overlying said threading slit.
20. A thread-case for sewing machine loop-takers, including a thread-cavity defining cup-shaped body having a cylindrical side wall provided with a threading slot and a threading slit, and an end wall, a tongue disposed within said body in spaced relation to said end wall to provide a thread-channel between said tongue and end wall leading to said side wall threading slit, said tongue being spaced from said side wall and having a threading slit extending from an edge thereof to a thread-guide connecting the cap-section thread-cavity with said thread-channel substantially centrally of said thread-cavity, and the threading slit in said tongue extending into said side wall threading slot.
21. A thread-case for sewing machine loop-takers comprising a cup-shaped base-section having a cylindrical side wall and an end wall, a cup-shaped cap-section separable from said base-section having a cylindrical side wall adapted to enter said base-section and having an end wall opposed to the base-section end wall to define a thread-cavity between said end walls, said cap-section side wall having a threading slit and a threading slot extending from the rim of the cup-shaped body thereof toward its end wall, a tongue disposed within said cap-section body in spaced relation to the end wall thereof to provide a thread-channel between said tongue and the cap-section end wall leading to said side wall threading slot, said tongue being spaced from said side wall of the cap-section and having a threading slit extending from an edge of the tongue to a thread-guide connecting the cap-section thread-cavity with said thread-channel substantially centrally of said thread-cavity, the threading slit in said tongue extending into said threading slot in the cap-section side wall, and a thread-tension spring upon the outer face of said cap-section in position to receive thread passing through said side wall threading slot from said cap-section thread-channel.
